UNITED STATES PATENT OFFICE.

EDWARD H. TATE, OF MALDEN, MASSACHUSETTS, ASSIGNOR TO TATE MANUFACTURING COMPANY, INC., OF BOSTON, MASSACHUSETTS, A CORPORATION OF MASSACHUSETTS.

MOP.

1,191,098.

Specification of Letters Patent. Patented July 11, 1916.

Application filed September 25, 1913. Serial No. 791,855.

To all whom it may concern:

Be it known that I, EDWARD H. TATE, a citizen of the United States, and a resident of Malden, county of Middlesex, and State of Massachusetts, have invented an Improvement in Mops, of which the following description, in connection with the accompanying drawings, is a specification, like characters on the drawings representing like parts.

This invention relates to mops, and more especially to so-called dry mops used for dusting floors, walls, ceilings, and furniture.

My invention will be best understood by reference to the following specification, when taken in connection with the accompanying drawings of one specific embodiment thereof, while its scope will be more particularly pointed out in the appended 20 claims.

In the drawings: Figure 1 is an elevation of a dry mop embodying my invention, showing the tuft of yarn as it rests upon the floor, and illustrating in full and dotted lines different positions which the handle can assume when in use. Fig. 2 is an elevation of the mop on an enlarged scale, with the handle removed, as viewed from the left of Fig. 1; Fig. 3 is a plan section on line 30 3—3 of Fig. 2, also on an enlarged scale, and with the handle removed; and Fig. 4 is a detail sectional view on line 4—4 of Fig. 3, illustrating the interengaging relation between the mop and its holder.

Referring to the drawings, and to the embodiment of my invention which I have selected for illustration, I have there shown a mop of the type commonly called a dry mop. The term mop is commonly used to 40 designate the entire device, including the tuft of yarn and its holder and handle, and is also often used to designate only the tuft of yarn, cloth, or other material, serving to scrub the surfaces to be cleaned. It will 45 be convenient hereinafter to use the word in the latter sense, and to refer to the mounting of the mop as the mop holder.

I have herein shown a mop, designated generally by the numeral 5, comprising a band 6 of cloth or other appropriate material, between the folds of which a bunch or tuft 7 of coarse yarn is inserted and held by one or more rows of stitches 8. I have 50 herein shown the band 6, wrapped about 55 and encircling a ring 9, provided with

flanges 10—10, between which is formed a circumferential groove 11, into which the band is fitted, as illustrated in Fig. 4. This interengaging relation between the band and the ring prevents the band from accidentally slipping off the ring when in use.

The band may be contracted about the ring by any other appropriate means, but herein the terminal portions of the band are adjustably secured to each other by a buckle 12, by means of which the terminal portions may be attached to each other in a plurality of predetermined positions of adjustment. This buckle herein comprises a member 13, provided with a series of apertures 14 to receive a tongue 15 hinged to a member 16. The member 13 is herein secured to one terminal portion of the band by a rivet 17, and the member 16 is herein secured to the other terminal portion of the hand by a rivet 18.

As a means for normally holding the tongue in the position illustrated in Figs. 2 and 3, it is herein provided with a short arm 20, having yielding engagement with a spring tongue 21 formed on the member 16. In assembling the mop, the band is wrapped about the ring, and the tongue 15 inserted in the proper aperture 14, so that when the tongue is then swung toward the position shown in Figs. 2 and 3, it will draw the terminal portions of the band toward each other, and cause the band to closely hug the ring. In fact, by this means, the band can be contracted so as to cause the same to enter into the circumferential groove 11, and thus interengage with the ring to lock the band against accidental removal. The mop is herein provided with a handle 22, which may be attached to the ring in any appropriate manner, but herein is threaded into a socket 23 provided in a member 24, located within and extending from side to side of the band, and provided with reduced terminal portions 25—25, extending through 100 opposite sides of the band.

If desired, its terminal portions may be provided with cotter, or other, pins 26, passing through the terminal portion outside the band. Preferably also the terminal portions are shouldered to abut against the inner surfaces of the band, as shown in Fig. 3. There is thus provided a pivotal attachment of the handle to the band, permitting the handle to be swung through an 110

angle of nearly 180 degrees, while still affording sufficient resistance to the swinging movement to prevent the mop from accidentally overturning with relation to the handle when in use.

It will now be apparent that by grasping the handle, the user may place the mop upon the floor, wall, ceiling, or other surface, whether it be in a horizontal or vertical 10 plane, or upon the upper or lower side of any object, and that the pivotal attachment of the mop to its handle is such that the mop will accommodate itself to the varying positions in which it is placed, and 15 will remain flat against the surface at all times when it is in use. It will also be evident that regardless of the height of the user, or the angular position in which the handle is held, or other variations in conditions of use, the mop will at all times automatically accommodate itself to such changes, without any special attention on the part of the user. One important advantage 20 is that the handle may be removed and the member 24 grasped and utilized as a handle, by means of which the mop may be manipulated. When so used, the user's thumb and fingers will of course extend down into the space within the ring, and in a most convenient manner. When used in this manner, 25 also, the mop will accommodate itself to the surface being cleaned, even though the member 24 be grasped firmly in the hand of the user.

30 When the mop is to be cleaned, it can be detached from its holder by simply unfastening the buckle and unwrapping the mop from the ring, and after being cleaned, can be instantly and conveniently returned to 35 its place, without the use of any tools.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific application herein shown, but 40 that extensive deviations from the specific form or embodiment of the invention may be made, without departing from the principles thereof.

Having thus described my invention, what 45 I claim and desire by Letters Patent to procure is:—

1. The combination of a mop-holder com-

prising a ring provided with a circumferential groove, a member located within said ring and having terminal portions extending through said ring into said circumferential groove and forming pivots for said member, means in said groove to secure said terminal portions to said ring, a handle attached to said member, a mop comprising 60 a band encircling said ring and located in said groove, and means to secure said band in place in said groove.

2. The combination of a mop-holder comprising a ring provided with a circumferential groove, a member located within said ring and having reduced terminal portions extending through said ring into said circumferential groove and forming pivots for said member, the latter being provided with 70 opposite shoulders engaging the inner circumferential surface of said ring, fastening means extending from said groove into said reduced portions, a mop comprising a band 75 encircling said ring and located in said groove, and means to secure said band in place in said groove.

3. The combination of a mop-holder comprising a ring provided with a circumferential groove, a member located within said 80 ring and having terminal portions extending through said ring into said circumferential groove and forming pivots for said member, means in said groove to secure said terminal portions to said ring, a handle attached to said member, a mop comprising a band 85 encircling said ring and located in said groove and engaging the ends of said terminal portions, and means to secure said band in place in said groove.

4. The combination of a mop-holder comprising a ring, a grasping member located within and pivoted to said ring but separated therefrom on two sides by spaces for the introduction of the hand of the user 100 and providing for the manipulation of the implement by grasp of the hand about the top, bottom and sides, of said grasping member, a mop encircling said ring, and means external to said ring to secure said mop 105 thereto.

In testimony whereof, I have signed my name to this specification, in the presence of two subscribing witnesses.

EDWARD H. TATE.
